ACCESS CONTROL HANDLE

Bob G. Harrell, St. Louis, Mo., assignor to The Jackes-Evans Manufacturing Company, St. Louis, Mo.

Filed July 14, 1972, Ser. No. 271,716

Term of patent 14 years

Int. Cl. D8—06

U.S. Cl. D8—148

FIG. 1 is a front perspective view of the access control handle of this invention;

FIG. 2 is a side elevational view of the access control handle shown in FIG. 1, the opposite side being substantially similar;

FIG. 3 is a front elevational view of the access control handle shown in FIG. 1;

FIG. 4 is a top plan view of the access control handle shown in FIG. 1;

FIG. 5 is a bottom plan view of the access control handle shown in FIG. 1; and,

FIG. 6 is a rear elevational view of the access control handle shown in FIG. 1, as seen through the locker door.

The broken lines in FIGS. 2 and 4—6 are for illustrative purpose only.

I claim:

The ornamental design for an access control handle, as shown and described.
